UNITED STATES PATENT OFFICE.

SHERMAN T. WALP, OF SUMMERFORD, OHIO.

SCREEN-FRAME.

No. 806,943.

Specification of Letters Patent.

Patented Dec. 12, 1905.

Application filed March 9, 1905. Serial No. 249,293.

To all whom it may concern:

Be it known that I, SHERMAN T. WALP, a citizen of the United States, residing at Summerford, in the county of Madison and State of Ohio, have invented a new and useful Screen-Frame, of which the following is a specification.

This invention relates to frames for window-screens and similar structures, and has for its object to provide a simply-constructed and easily applied and operated device which may be quickly inserted into and removed from a window-frame and which when locked in position will be removable only from the inside 15 of said window-frame.

With these and other objects in view, which will appear as the nature of the invention is better understood, the same consists in certain novel features of construction, as herein- 20 after fully described and claimed.

In the accompanying drawings, forming a part of this specification and in which corresponding parts are denoted by like designating characters, is illustrated the preferred 25 form of embodiment of the invention capable of carrying the same into practical operation, it being understood that the invention is not necessarily limited thereto, as various changes in the shape, proportions, and general assem- 30 blage of the parts may be resorted to without departing from the principle of the invention or sacrificing any of its advantages.

In the drawings, Figure 1 is a transverse section on the line 1 1 of Fig. 2. Fig. 2 is an 35 elevation of a portion of a window-frame and one of the sashes with the improved screen-frame in position in the window-frame.

The screen-frame, which is represented at 10, may be of any required size and is pref- 40 erably formed with one of the side members divided longitudinally, the divided portion 11 being connected to the adjacent stationary side member by hinges 12 13, so that it will swing in only one direction upon said station- 45 ary side member. The divided portion 11 is provided with a stop-plate 14, extending laterally from its hinged side, and the adjacent stationary side member provided with a locking member 15, having a longitudinal slot 16, 50 through which clamp-screws 17 18 are inserted into the screen-frame to provide for the vertical movement of the locking member. The locking plate or member is also provided with a lateral projection 19 for bearing against the 55 stop-plate 14 when said locking-plate is in one position and releasable therefrom when the

locking-plate is in its other position. By this means when the projection 19 is in position bearing against the stop-plate, as shown in full lines in Figs. 1 and 2, the divided portion 60 11 will be rigidly supported in transverse alinement with the remainder of the screen-frame; but when the position of the locking-plate is reversed, as indicated by dotted lines in Fig. 2, the divided portion may be turned 65 at an angle to the remainder of the screen-frame, as indicated by dotted lines in Fig. 1.

The screen-frame, together with its divided portion 11, will just fit in between the sides 70 21 of the window-frame, preferably beneath the upper sash, a portion of which is indicated at 22, with the sash member bearing upon the screen-frame and its divided portion, while the latter rests upon the window-sill, (represented at 23.)

When the screen-frame is to be inserted, the locking member 15 is moved upward to release the stop 14 and permit the hinged member 11 to be folded toward the body of the frame, and thus reduce the width of the 80 frame, so that said frame will pass the parting-stop 24 and be positioned beneath the upper sash and outside the path of the lower sash. The divided portion 11 is then replaced in position in transverse alinement with the 85 remainder of the screen-frame and the locking-plate permitted to drop into position, with its projection 19 bearing against the stop-plate 14, which firmly locks the screen-frame in place and prevents its removal until the 90 locking-plate is released. The locking-plate and stop-plate being upon the inner and hinged side of the screen-frame, it is obvious that the latter cannot be removed or tampered with from the outside.

The member 14 will not project far enough to obstruct the movement of the lower sash, so that the presence of the improved frame will not interfere with the ordinary movements of the same.

It will thus be noted that a simply-constructed and easily applied and operated device is produced which will effectually protect the building to which they are applied from flies, mosquitoes, and other insects, and 105 one which cannot be removed from the outside.

Having thus described the invention, what is claimed is—

1. A screen having one of its side members 110 divided longitudinally and hinged together, a stop-plate extending laterally from the hinged

side of said divided portion, and a vertically-adjustable member secured to said frame and adapted to engage the stop-plate for locking said divided portion in transverse alinement 5 with the adjacent side member of the screen-frame.

2. A screen-frame having one of its side members divided longitudinally and hinged together, a stop-plate extending laterally from the hinged side of said divided portion, and a vertically-adjustable locking member secured to the frame and provided with a lateral projection adapted to engage the stop-plate for locking said divided portion in transverse alinement 10 with the adjacent side member of the screen-frame.

3. A screen-frame having one of its side

members divided longitudinally and hinged together, a stop-plate extending laterally from the hinged side of said divided portion, 20 a locking member having a longitudinal slot and movably connected to said screen-frame by screws passing through said slot and provided with a lateral projection for bearing against said stop-plate when the lock-plate is 25 in one position and detachable therefrom when the stop-plate is in another position.

In testimony that I claim the foregoing as my own I have hereto affixed my signature in the presence of two witnesses.

SHERMAN T. WALP.
